UNITED STATES PATENT OFFICE.

EDWIN H. PIERSEN, OF TOPEKA, KANSAS, ASSIGNOR TO THE PIERSEN MANUFACTURING COMPANY, OF TOPEKA, KANSAS, A CORPORATION OF KANSAS.

PERFORATOR.

1,393,243.

Specification of Letters Patent. Patented Oct. 11, 1921.

Carved out of the application on which Patent No. 1,289,900 was granted on December 31, 1918, and filed after grant of that patent. This application filed October 2, 1919, Serial No. 328,050. Renewed August 25, 1921. Serial No. 495,260.

To all whom it may concern:

Be it known that I, EDWIN H. PIERSEN, a citizen of the United States, residing at Topeka, in the county of Shawnee and State 5 of Kansas, Box 413, have invented certain new and useful Improvements in Perforators; and I do declare the following to be a full, clear, and exact description of the invention, such as will enable others skilled 10 in the art to which it appertains to make and use the same, reference being had to the accompanying drawings, and to the letters and figures of reference marked thereon, which form a part of this specification.

15 My invention relates to perforators.

Generically, the invention contemplates the provision of means whereby a mechanism may be manually operated to perforate fragile sheets, ribbons, or tapes although it 20 is particularly adapted for preparing tapes or ribbons for use in transmitting telegraphic characters, with apparatus like that shown in my U. S. Patent No. 1,289,900, of December 31, 1918, of which this is a division, filed after grant of the patent, to 25 which reference may be had for a better understanding of the use of the tape after it has been perforated.

Although the invention is capable of manipulation to prepare sheets, ribbons, or tapes for various uses, I will describe it in connection with tapes to be prepared for use in telegraph transmitters. For such use, the tapes are first punched to provide apertures corresponding to the dots and dashes of telegraph characters in order that when the tape is passed along a circuit making and breaking device, electrical impulses may be passed to the transmission line in character groups.

In carrying out my invention I may utilize a digitally operated mechanism which, under certain conditions, may comprise an ordinary typewriter key board, the levers 45 of which are provided with male punch die members that coöperate with female complementary die members to effect the perforation of the tape in character groups as the tape is moved between the die members in stepped travel.

It is apparent that the advance of the tape must vary according to the length of the characters in order to maintain uniform spaced relation between character groups ir-

respective of the length of the characters. 55 Such differential movement may be effected in any suitable manner but preferably in that illustrated in my prior Patent 1,289,900 and in my application relating to the variable escapement filed concurrently herewith. 60

In the drawings forming part of this specification:

The single figure illustrates the present invention consisting of key levers, punch dies and a complementary die, the tape advancing mechanism being represented by the forwarding rollers, although I do not wish to be limited to any particular form of tape feed.

Referring more in detail to the drawings, 70

1 designates a frame within which the perforating parts may be mounted. The frame is provided with a vertical rail 2, having grooves 3, within which key levers 4 are seated and pivotally mounted on a fulcrum rod 5 that preferably extends through all of the bearings 6. The forward end of each key lever is up-turned and provided with a button 7 bearing the designation of the character it represents. 80

Back of the rail 2 is a second rail 8 having grooves 9 corresponding in number and arrangement with the grooves 3 in rail 2 and within which the rear ends of the levers 4 may be guided to insure registration 85 of the movable punch die members on the levers with corresponding portions of the complementary die member. The levers 4 are preferably struck from sheet metal and include die teeth 10 on their upper edges, 90 near their rear ends. The die teeth are of such length and arrangement as to correspond with the dots and dashes of the Morse or other telegraphic code. For example, the key lever at the front of the view in the 95 present drawing is adapted to perforate the "h" character consisting of four dots, the second key lever the character "n" consisting of a dash and dot; the other key levers being arranged for perforating 100 groups of apertures corresponding to the letters or characters represented by those particular keys.

Located above the key levers, a sufficient distance to permit the passage of a tape and 105 permit clearance of the punch dies, is a stationary complementary die 11, comprising a plate 12 that extends transversely of the

levers and contains groups of apertures 13 corresponding to the punch dies 10 of the several key levers. For illustration, the portion of the plate 12 located directly above the "h" key lever contains four short apertures separated by the standard telegraphic spaces and corresponding to the four short die teeth on the "h" key lever. A portion of the plate adjacent that just mentioned contains a long and a short aperture corresponding to the dash and dot of the "n" character and the remainder of the plate is similarly apertured to correspond with the dies on the remaining key levers.

15 In the form of apparatus selected for illustration, a rail 14 is shown as attached to each longitudinal edge of the complementary die plate and rising therefrom to form a trough for the tape punchings to prevent their overflow into the mechanism. One means of advancing the tape is here shown as consisting of contacting, paired rollers 15, one or both of which may be rotated by any suitable means (not shown) to effect friction drive of the tape. The tape 16 may be fed from a roll 17 having revoluble mounting on a rod 18 extending transversely of the machine and over a guide rod 19 adjacent the counter-die to properly guide and tension the tape during the perforating and advancing operations. A spring 20 is connected with each lever 4 and anchored to the base of the frame to return the levers after each individual operation.

In using the device, assuming the parts to be constructed and assembled as described, when a key lever is operated by pressure on its button 7, the front end of the lever 4 is lowered and its rear end elevated to throw the punch dies 10 of that particular lever into the corresponding apertures 13 of the complementary die plate 12. As the tape is located between the levers and the complementary die 12, elevation of the punch dies causes them to engage and penetrate the tape, forming apertures therein corresponding to the latter or other character represented by the particular key lever that is operated, the levers being brought back to their normal inactive position by the spring 20. Operation of key levers in sequence will in this way form a record on the tape which, when the tape is passed along a circuit making and breaking device, will be transferred to a telegraph line and effect the transmission of a message.

In the foregoing description I have described the dies as effecting perforation of the sheet or tape to be treated, but it is obvious that the complete passage of the male die member through the tape under certain conditions may not necessarily be effected. For example, the blow against the tape may be light enough, or the female die

member may be provided with shallow recesses instead of perforations so that simply the impression of the die character on the lever will be embossed on the sheet; therefore, whenever the word "perforation" or 70 an expression of like import is used, it is to be understood that it contemplates either an actual perforation of the sheet or a disruption of the initial cross sectional area thereof.

75 In order to adapt the device for embossed tape, I preferably provide grooves 21 in the forwarding rollers 15 in line of the treated portions of the tape. This prevents ironing out upset portions of the tape, without detracting from their forwarding function.

80 While I have referred to mechanism for feeding the tape intermittently, a circuit making and breaking device, etc., I have not illustrated such parts herein as they form 85 no part of the present invention and as reference may be had to my former application for forms of such parts.

Having thus described my invention what I claim as new therein and desire to secure 90 by Letters-Patent is:

1. A perforator comprising a plurality of 95 digitally operated levers, each lever having character indicia on one end and a corresponding character on the opposite end, a complementary die member coöperating therewith, and means for conducting a tape between the die members.

2. A perforator comprising a plurality of 100 digitally operated levers, each lever having character indicia on one end and a corresponding die character on the opposite end, a rigid complementary die member coöperating therewith, and means for conducting a tape between the die members.

105 3. In a perforator, a complementary die having a plurality of sets of apertures dimensioned and grouped to correspond with indicia of a telegraphic code, a key lever for each set of teeth thereon, dimensioned and grouped to correspond with the complementary die set, and means for conducting a tape between the die members.

110 4. In a perforator, a complementary die having sets of character openings corresponding with dots and dashes of a telegraphic code, a key lever for each set of openings, having an index at one end and a set of character teeth at the other end, the character teeth adapted, when the lever is operated, to register with the openings in a corresponding complementary die set.

115 5. In a perforator, a complementary die, comprising a trough-shaped member having a plurality of sets of apertures dimensioned and grouped to correspond with indicia of a telegraphic code, a die member for each complementary die set, having a set of teeth thereon, dimensioned and grouped to cor- 120 125 130

- respond with the complementary die set, operable from beneath the complementary die member to extrude punchings into the trough of the complementary member.
- 5 6. In a perforator, a complementary die comprising a trough-shaped member having a plurality of sets of apertures, dimensioned and grouped to correspond with indicia of a telegraphic code, a key lever for
10 each complementary set, having a function-

ing portion operable from beneath the complementary member and having a set of teeth thereon, dimensioned and grouped to correspond with the complementary set, to extrude punchings into the trough of the 15 complementary member, and means for conducting a tape between the die members.

In testimony whereof I affix my signature.

EDWIN H. PIERSEN.
